ENGINE STARTER

John W. Fitz Gerald, Milwaukee, Wis., assignor to
 Briggs & Stratton Corporation, Milwaukee,
 Wis., a corporation of Delaware

Application May 20, 1942, Serial No. 443,731

8 Claims. (Cl. 74—6)

This invention relates to engine starters and refers particularly to so-called manual starters wherein the pinion is manually moved into mesh with the ring gear before the starter motor starts.

Starters of this type are generally preferred for engines that do not start readily, for by holding the starter pedal "in" the pinion can be held in mesh notwithstanding initial starting spurts which would demesh a starter of the automatic type.

However, this feature of the manual type of starter has its disadvantage in that the starter mechanism and starting motor are apt to be subjected to excessive strain and wear if the starter is kept in mesh after the engine starts, which often occurs at the hands of inexperienced drivers.

It is, therefore, an object of this invention to provide a starter of the manual type which incorporates means for automatically demeshing the pinion upon proper starting of the engine.

More specifically it is an object of this invention to provide a starter of the character described wherein a centrifugally responsive latch holds the pinion in mesh (providing the starter pedal is kept depressed) until the pinion driven by the engine attains a predetermined speed of rotation.

It is also an object of this invention to provide a starter of the character described having means incorporated therein for yieldingly compensating for accidental collision of the teeth on the pinion and ring gear.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a view partially in side elevation and partially in horizontal section illustrating a starter embodying this invention and showing the pinion in its inoperative position;

Figure 2 is a view similar to Figure 1 but showing the manner in which accidental collision be-

tween the pinion and ring gear teeth is yieldingly accommodated;

Figure 3 is a view similar to Figure 2 showing the pinion fully meshed; and

Figure 4 is a detail cross sectional view through Figure 1 on the plane of the line 4—4.

Referring now particularly to the accompanying drawings, in which like numerals indicate like parts, the numeral 5 designates the ring gear of an engine to be started with which a pinion 6 is adapted to be meshed upon manual depression of a starter pedal 7.

It is to be understood, however, that in place of the manually depressible pedal 7 suitable electromagnetic means or its equivalent may be employed to shift the pinion into mesh with the ring gear.

The pinion 6 is carried by a sleeve 8 freely slidably splined to the shaft 9 of the starter motor 10. The motor 10 is mounted within a housing 11 equipped with bearings 12 and 13 at its opposite ends to support the motor shaft, the latter bearing also serving to mount the sleeve 8 which carries the pinion.

Between the bearing 13 and the adjacent end of the motor 10, the sleeve 8 has an enlargement 14 which is transversely slotted to receive diametrically opposite ribs 15. The ribs 15 may be an integral part of the motor shaft, but preferably consist of axial projections on a collar 16 keyed or otherwise secured to the motor shaft. The interengagement of the ribs 15 and the slots in the enlargement 14 provide the splined driving connection between the motor shaft and the pinion sleeve.

Enclosing the enlargement 14 is a barrel member 17 the closed end 18 of which is bored and notched to receive the shaft 9 and the ribs 15 of the collar 16. The barrel thus revolves with the motor shaft and pinion. Inside the barrel a compression spring 19 is confined between the inner walls of the barrel and the enlargement 14 on the pinion sleeve. The ends of this spring bear against a spring ring 20 fixed on the enlargement 14 and a flange 21 secured to the open end of the barrel and extending across the annular space between the mouth of the barrel and the enlargement 14.

Loosely mounted on the barrel so as to be free to move axially thereon is a spanner ring 22. This ring is preferably splined to the barrel in any suitable manner as by a pin 22' carried by the ring and engaging in a longitudinal groove 17' but is restrained against axial motion on the barrel by a weighted pin 23 slidable in a radial

hole 24 in the spanner ring and projecting into a socket 25 in the outer cylindrical surface of the barrel.

A leaf spring 26 anchored to the spanner ring presses against the weighted pin to yieldingly hold the same engaged in the socket 25 to secure the spanner ring and barrel against relative axial movement.

The spanner ring 22 also has an annular groove 21 with which a fork 28 actuated by the 10 starter pedal 7 cooperates to shift the entire pinion assembly axially to mesh the pinion with the ring gear upon depression of the starter pedal. During such axial shifting of the pinion assembly a heavy compression spring 29 encircling the 15 collar 16 and confined between the motor 10 and the adjacent end of the barrel is compressed or loaded.

In the event the pinion and ring gear teeth collide as illustrated in Figure 2, depression of 20 the starter pedal may continue by virtue of the axial yieldability provided by the spring 19.

Upon final and complete depression of the pedal 7 the circuit to the starter motor 10 (not shown) is closed by depression of a switch plunger 30. In the event of improper engagement as indicated in Figure 2, the initial starting of the motor 25 promptly aligns the pinion and ring gear teeth.

After proper engagement of the pinion and gear and the starter motor begins to turn over the engine, the pedal 7 may be held in indiscriminately without danger of damage to the starter mechanism for the instant the speed of rotation of the pinion driven by the ring gear exceeds a predetermined value, centrifugal force acting on the weighted pin 23 disengages the pin from the socket 25 and releases the pinion assembly for projection to its normal demeshed position by the loaded compression spring 29. It is, of course, understood that the spanner ring 22 and consequently the pin 23 revolve with the pinion, so that it is the speed of rotation of the pinion which determines when the pinion is released for disengagement from the ring gear.

Re-engagement of the pin 23 in the socket 25 to 45 again couple the spanner ring to the barrel is accomplished by the starter pedal sliding the spanner ring back along the barrel as the pedal is restored to its normal position where it is held by a spring (not shown).

From the foregoing description, taken in connection with the accompanying drawings, it will be readily apparent to those skilled in the art, that this invention provides an engine starter of the so-called manual type which incorporates the 55 advantages of the manual starter with those of the automatic starter and in addition assures the pinion being retained in mesh with the ring gear until the engine actually starts.

What I claim as my invention is:

1. In an engine starter of the manual type having a pinion manually meshed with the ring gear before the circuit to the starting motor is closed, the combination of: a spring urging the pinion to an out-of-mesh position; a manually operable actuator; means for closing the circuit of the starting motor by the final movement of the actuator; a releasable connection between the actuator and a part movable both axially and rotarily with the pinion whereby the pinion may be moved into mesh by the actuator and released for demeshing independently of the actuator, said releasable connection including a centrifugally responsive latch carried by a part revolving with the pinion and through which motion of the ac-

tuator is transmitted to the pinion part and consequently to the pinion, said centrifugally responsive latch being operable to disrupt the connection between the actuator and said pinion part when the pinion attains a predetermined speed of rotation.

2. In an engine starter of the character described, the combination of: a starting motor; a pinion movable axially into and out of mesh with the ring gear of an engine to be started; means at all times drivingly connecting the pinion with the starting motor; actuating means for moving the pinion into mesh with the ring gear; a releasable motion transmitting connection between the actuating means and the pinion, said releasable motion transmitting connection including a centrifugally responsive latch carried by a part revolvable with the pinion, response of said latch to centrifugal force upon the attainment of a predetermined speed of rotation of the pinion disrupting said motion transmitting connection; and yieldable means for moving the pinion out of mesh with the ring gear upon disruption of said releasable connection between the pinion and said actuating means.

3. In an engine starter of the character described: a motor driven power shaft; a pinion movable axially to and from an operative position meshing with the ring gear of an engine to be started; means at all times drivingly connecting the pinion with the power shaft; an actuator for moving the pinion axially to its operative position; a spring biasing the pinion axially out of its operative driving position, said spring 35 being loaded by movement of the pinion to operative position; an axially slidably, but non-rotatable, connection between the actuator and a part movable with the pinion; and a releasable motion transmitting connection between said part and the actuator including a centrifugally responsive latch carried by the actuator so as to be rotatable with the pinion, response of the latch to the centrifugal force prevalent when the pinion attains a predetermined speed of rotation disrupting the motion transmitting connection and freeing the pinion for demeshing under the influence of said biasing spring.

4. In an engine starter of the character described: a motor driven power shaft; a pinion having a slidably splined driving connection with the power shaft allowing for axial motion of the pinion with respect to the power shaft; a spring tending at all times to hold the pinion in a demeshed non-driving position; and means for moving the pinion against the action of said spring to an active driving position including drivingly connected, but relatively axially movable parts rotatable with the pinion, and a centrifugally responsive latch carried by one of said 50 parts and releasably engaging the other part for normally releasably holding said parts against relative axial motion so that upon actuation of said pinion moving means the pinion is slid into driving position, response of said latch to centrifugal force, upon the pinion attaining a predetermined speed of rotation, releasing said parts for relative axial motion and freeing the pinion for projection by said spring to its inactive non-driving position.

5. In an engine starter of the character described: a pinion movable axially to and from an operative position; a spring reacting axially against the pinion and loaded during movement of the pinion to operative position so as to yieldingly urge the pinion out of its operative posi-

tion; a barrel member coaxial with the pinion; means connecting the barrel member with the pinion so that the barrel member is movable with the pinion; a movable actuating member slidably splined to the barrel member; and a centrifugally responsive latch carried by one of said members so as to rotate with the pinion and engaging the other member to effect a motion transmitting connection between the members so that axial motion of the actuating member in one direction shifts the pinion to its operative position while response of the latch to centrifugal force disrupts the motion transmitting connection and frees the pinion for spring propelled movement out of its operative position.

6. In an engine starter: a power shaft; a pinion movable axially of the power shaft to and from an operative position; complementary telescoped relatively axially movable parts, one of which is fixed with respect to the pinion; means constraining both said parts to turn with the power shaft while leaving them free to slide thereon; stop means on said telescoped parts limiting relative axial movement thereof in one direction; a spring reacting between said parts to normally hold the same in said relative positions defined by the stop means, said spring allowing said parts to move axially with respect to each other in the event of pinion tooth interference during pinion shifting movement applied to the other of said parts; a spanner ring slidably splined to said other one of said complementary telescoped parts; manually operable means engaging the spanner ring for shifting the same in a direction to move the pinion to its operative position; a centrifugally responsive latch rotatable with and providing a releasable connection between the spanner ring and said part to which it is slidably splined, response of the latch freeing the complementary parts and the pinion for axial movement with respect to the spanner ring; and a spring reacting axially against the complementary parts to move the same and consequently the pinion out of operative position the instant the centrifugal latch responds.

7. In an engine starter of the type having a pinion at all times drivingly connected with a starting motor: a member connected with the pinion to be movable therewith; means for shifting the pinion into mesh with the ring gear of an engine to be started before the starting motor begins to operate, said means including a ring member slidably splined to said member connected with the pinion, and a centrifugally responsive latch carried by one of said members to turn therewith and engaging the other member to provide a releasable motion transmitting connection between said members, response of the latch to a predetermined speed of rotation of said members and the pinion releasing the pinion from the shifting means; and means at all times exerting a biasing force on the pinion to move the same to its demeshed position upon such response of the latch.
8. In an engine starter of the character described: a pinion movable axially to and from an operative position; a spring loaded during movement of the pinion to operative position; a barrel member; means connecting the barrel member with the pinion so that the barrel member moves with the pinion; another member slidably but nonrotatably, connected with said barrel member so that said members at all times rotate together and with the pinion; actuating means connected to said other member for shifting the same axially; and a centrifugally responsive latch carried by one of said members to be rotatable with the pinion and engaging the other member to normally releasably connect the members so that the pinion may be shifted to its operative position by actuation of said other member, response of the latch to the centrifugal force prevalent at a predetermined speed of rotation of the pinion disrupting said connection between said members and releasing the pinion for movement out of its operation position.

JOHN W. FITZ GERALD.
